Primary Examiner — Cynthia Ramirez*Assistant Examiner* — Gino Colan(57) **CLAIM**

The ornamental design for a valve body, as shown and described.

DESCRIPTION

FIG. 1 is a perspective view of a valve body showing our new design.

FIG. 2 is a front elevational view thereof.

FIG. 3 is a rear elevational view thereof.

FIG. 4 is a side elevational view thereof.

FIG. 5 is a side elevational view of a side opposite that shown in FIG. 4.

FIG. 6 is a top plan view thereof; and,

FIG. 7 is a bottom plan view thereof.

The broken lines represent environment that forms no part of the claim.

1 Claim, 4 Drawing Sheets(56)
